US0D1069698S

(12) **United States Design Patent** (10) **Patent No.:** **US D1,069,698 S**
(45) **Date of Patent:** **** Apr. 8, 2025**

(54) **WIRELESS CHARGING MOUNT**

(71) Applicant: **ANNEX PRODUCTS PTY. LTD.**,
South Yarra (AU)

(72) Inventors: **Alex Morrison**, South Yarra (AU);
Andrew Kellock, South Yarra (AU)

(73) Assignee: **ANNEX PRODUCTS PTY. LTD.**,
South Yarra (AU)

(**) Term: **15 Years**

(21) Appl. No.: **29/887,062**

(22) Filed: **Mar. 16, 2023**

(51) **LOC (15) Cl.** **13-02**

(52) **U.S. Cl.**

USPC **D13/108**; D14/253

(58) **Field of Classification Search**

USPC D13/103, 107, 108, 118, 119, 137.1,
D13/137.2, 139.1, 144, 183; D12/415;
D14/447, 251, 252, 253

CPC .. H02J 7/0044; H04B 1/3877; H01R 2201/00

See application file for complete search history.

(57) **CLAIM**

The ornamental design for a wireless charging mount as shown and described.

DESCRIPTION

FIG. 1 is an upper perspective view of a wireless charging mount in accordance with our new design;

FIG. 2 is a left side elevation view of the wireless charging mount of FIG. 1;

FIG. 3 is a right side elevation view of the wireless charging mount of FIG. 1;

FIG. 4 is a rear elevation view of the wireless charging mount of FIG. 1;

FIG. 5 is a front elevation view of the wireless charging mount of FIG. 1;

FIG. 6 is a top plan view of the wireless charging mount of FIG. 1; and,

FIG. 7 is a bottom plan view of the wireless charging mount of FIG. 1.

The broken lines depict portions of the wireless charging mount that form no part of the claimed design.
